UNITED STATES PATENT OFFICE

WORLEY W. BARLOW, OF CHUCKEY, TENNESSEE

TOBACCO STICK HANDLING DEVICE

Application filed April 17, 1930. Serial No. 445,103.

The invention relates to means for handling tobacco sticks in drying barns and has for its object the provision of an improved construction of handling device that is reasonable in cost of manufacture and adapted to effectively support a stick while being moved from a wagon or truck to the barn and to enable the handler to locate the stick on racks in elevated positions in the barn.

The invention will be described in detail hereinafter and will be found illustrated in the accompanying drawings, in which

Figure 1 is a view in perspective of the improved tobacco stick handling device, and

Figure 2 is a view in elevation of the upper fragment of the handling device showing a tobacco stick in position thereon.

In the drawings, similar reference characters are used to designate corresponding parts in both views.

20 The tobacco stick handling device comprises a pole or rod 1 having two metal rods designated 2 secured as shown at 3 to opposite sides of the pole or rod 1, the intermediate portions of said rod, forming the arms of the 25 handling device, being inclined outwardly from each other and upwardly in relation to the end of the pole or rod 1 as shown at 4, and the extremities bent on substantially parallel lines as shown at 5. The extremities 30 5 are split at their outer ends inwardly of the rod 2, and the split portions are curved outwardly from each other as shown at 6, forming forks 7 to receive a tobacco stick 8 for location on a rack in the drying or curing barn.

35 What is claimed is:—

A tobacco stick handling device, comprising a pole, arms secured at one end of the pole and on opposite sides thereof, each of 40 said arms deflected outwardly away from one another on opposite sides of the axis of the pole, and having their outer ends deflected to substantial parallelism, and the extremities of said arms provided with oppositely and outwardly curved fingers providing supports for opposite ends of a tobacco stick, said fingers being curved laterally of the lines of parallelism of said ends.

45 In testimony whereof I affix my signature.

50 WORLEY W. BARLOW.
